UNITED STATES PATENT OFFICE.

FRANK E. KRAFT, OF KANSAS CITY, MISSOURI.

DRY-ROOM TUMBLER.

Application filed February 28, 1921. Serial No. 448,288.

My invention relates to dry room tumblers for use in laundries, and one object is to provide a relatively simple apparatus of this character whereby clothes and other washed articles can be dried more quickly and economically than heretofore.

A further object is to provide an apparatus of this character embodying a plurality of individual receptacles each adapted to hold the wash of a family, so that clothes belonging to different families will not become mixed.

The invention, broadly speaking, consists of a long drying chamber provided with rotary skids slightly inclined, on which the receptacles are caused to rotate and slowly pursue a path from end to end of said chamber; suitable doors or windows arranged adjacent to the ends of the chamber for the introduction and removal of the containers; means for heating the air in the chamber; means for circulating the hot air throughout the chamber; and one or more openings for the escape of the moist air from the chamber.

Other features will hereinafter appear, and in order that the invention may be fully understood, reference will now be had to the accompanying drawings, in which:

Fig. 1 is a broken side elevation of the apparatus.

Fig. 2 is a broken longitudinal section of the apparatus, with the blower removed.

Fig. 3 is a front elevation.

Fig. 4 is a cross section on line IV—IV of Fig. 1, with the receptacle in elevation.

Fig. 5 is a central section of one of the receptacles.

Fig. 6 is a detail elevation of a blower for circulating the hot air throughout the drying chamber.

In carrying out the invention, I employ a long drying chamber 2, which may rest directly upon the floor A of the building, or upon blocks 4 as shown. The chamber 2 consists, preferably, of a wooden jacket 6 provided with a sheet metal lining 8. In cross section the upper portion of the chamber 2 is, preferably, substantially semicircular as disclosed on Figs. 3 and 4, while the lower portion tapers downwardly and forms a hot air duct 10 extending the length of said chamber 2. The hot air duct 10 is provided with heating coils 12, which connect with a header 14 having a valve controlled inlet pipe 16 and a valve controlled

outlet pipe 18 to regulate the inflow and the outflow, respectively, of the steam or other heating agent.

20 designates a pair of rotary skids spaced apart at the upper portion of the hot air duct 10 and extending longitudinally through the chamber 2, through the end walls of which they project. The ends of the rotary skids 20 are reduced and journaled in bearings 22 and 24 adjacent to the front and rear walls, respectively, of the chamber 2. The forward journals of the rotary skids 20 are provided with fixedly-mounted pulleys 26, one of which drives the other through the intermediacy of a belt 28. One of said journals is also provided with a fixedly-mounted drive pulley 30, which may be driven by a suitable motor (not shown) through the intermediacy of a belt 32. As shown more clearly on Fig. 2, the rotary skids 20 are slightly inclined from front to rear. This inclination coacts with the rotary motion of the skids 20 in carrying receptacles 34 from the front to the rear of the chamber 2.

The receptacles 34 are of cylindrical form and made, preferably, of wire-cloth reinforced by bands 36, and each is provided at one end with a hinged lid 38 having a fastening device 40 for securing it in closed position. The receptacles 34 are placed in the front end of the chamber 2 and upon the rotary skids 20 through an opening 42 and removed from the rear end of the chamber 2 through an opening 44. The openings 42 and 44 are normally closed by windows 46 and 48 mounted in slideways 50 and 52, respectively, secured to one side of the chamber 2. The engagement of the bands 36 with the skids 20 will assist in the rotation and sliding movement of the receptacles.

54 designates a blower having an inlet pipe 56 leading from the upper rear portion of the chamber 2 and a discharge pipe 58 leading to the rear end of the hot air duct 10. The blower 54 has an opening 60 for taking in dry air from outside of the chamber 2.

The operation, briefly stated, is as follows: The receptacles 34 containing articles to be dried are passed one by one through the opening 42 at one end of the chamber 2, and placed upon the rotary skids 20, which rotate said receptacles and at the same time conduct them down to the opening at the opposite end of said chamber 2,

where they are removed. As the receptacles 34 pursue a course slowly down the skids 20 the articles are agitated by the rotary movement and are thereby thoroughly exposed to the hot air arising from the coils 12 and circulated through the receptacles 34 by the blower 54, so that by the time said receptacles 34 reach the opening 44 the articles are thoroughly dried. An opening 10 62 is provided in the lower portion of the chamber 2 to allow the heavy air laden with moisture from the articles being dried, to escape so that it will not retard the drying of said articles. The window 48 enables 15 the operator to observe the receptacles 34 as they successively approach the rear end of chamber 2.

From the foregoing description it will be readily understood that I have provided a 20 drying apparatus of large capacity, and one which is simple in construction and economical to maintain and operate, and while I have shown and described the preferred construction of my invention, I reserve the 25 right to make such changes and modifications as properly fall within the spirit and scope of the claims.

Having thus described my invention, what I claim and desire to secure by Letters Patent is:

1. In apparatus of the character described, a receptacle for holding work to be dried, a drying chamber, and means for effecting rotary movement and endwise travel of said receptacle through said drying chamber.
2. In apparatus of the character described, a receptacle for holding work to be dried, a drying chamber, and inclined 40 means for effecting rotary movement and endwise travel of said receptacle through said drying chamber.
3. In apparatus of the character described, a receptacle for holding work to be dried, a drying chamber, and parallel means for effecting rotary movement and endwise travel of said receptacle through said drying chamber.
4. In apparatus of the character described, a receptacle for holding work to be dried, a drying chamber, and parallel inclined means for effecting rotary movement and endwise travel of said receptacle through said drying chamber.
5. In apparatus of the character described, a receptacle for holding work to be dried, a drying chamber, and a single means for effecting rotary movement and endwise travel of said receptacle through said drying chamber.

6. In apparatus of the character described, a receptacle for holding work to be dried, a drying chamber, and rotary means for effecting rotary movement and endwise travel of said receptacle through said drying chamber. 65

7. In apparatus of the character described, a receptacle for holding work to be dried, a drying chamber, and means for effecting the travel of said receptacle endwise through said drying chamber and along said means. 70

8. In apparatus of the character described, a receptacle for holding work to be dried, a drying chamber, and means for effecting the travel of said receptacle endwise through said drying chamber and along said means and for effecting rotary movement of said receptacle during such travel. 75

9. In apparatus of the character described, a receptacle for holding work to be dried, a drying chamber, and a pair of members arranged in said chamber for effecting travel of said receptacle endwise 85 through said chamber, said members being rotatable about axes longitudinally disposed with respect to said drying chamber.

10. In apparatus of the character described, a receptacle for holding work to be dried, a drying chamber, and means for effecting travel of said receptacle endwise through said drying chamber and for effecting the agitation of the work in said receptacle during the travel of said receptacle 95 through said chamber.

11. In apparatus of the character described, a drying chamber having an opening in its lower portion for the escape of moist air, a receptacle for holding work to be dried, inclined rotary means for effecting the travel of said receptacle endwise through said drying chamber, operating means for said rotary means, a hot air duct longitudinally disposed within the lower 105 portion of said chamber, heating coils arranged in said air duct, and means for circulating air throughout said drying chamber.

12. In apparatus of the character described, a receptacle for holding work to be dried, a drying chamber having normally closed openings through which said receptacle may be inserted and removed, and means for effecting the travel of said receptacle endwise through said drying chamber. 110 115

In testimony whereof I affix my signature.

FRANK E. KRAFT.
